UNITED STATES PATENT OFFICE

170,859

CLOCK

Irving B. Hall, Chicago, Ill.

Application November 28, 1952, Serial No. 22,484

Term of patent 14 years

(Cl. D42—7)

To all whom it may concern:

Be it known that I, Irving B. Hall, a citizen of the United States, residing at Chicago, county of Cook, Illinois, have invented a new, original, and ornamental Design for a Clock, of which the following is a specification, reference being had to the accompanying drawing, forming a part hereof.

Figure 1 is a front view;

Figure 2 is a side view;

Figure 3 is a rear view; and

Figure 4 is a top view of a clock, showing my new design, the dominant features of which are shown in solid lines.

I claim:

The ornamental design for a clock, as shown and described.

IRVING B. HALL.
